CONTROL CIRCUIT WITH TWO-POSITION SWITCH FOR LATCHING CIRCUIT BREAKER

Russell W. Stineman, Seattle, Wash., assignor to Boeing Airplane Company, Seattle, Wash., a corporation of Delaware

Application May 14, 1956, Serial No. 584,556

2 Claims. (Cl. 317—54)

This invention relates to improvements in control circuits for latching circuit breakers, and more particularly concerns such a circuit incorporating manually operated switch means arranged to close or trip the circuit breaker selectively and by its setting to indicate visually the condition of said circuit breaker. The invention is herein illustratively described by reference to the presently preferred form thereof; however, it will be recognized that certain modifications and changes therein with respect to details may be made without departing from the essential and characterizing features involved.

In past practice the trip coil of the latching circuit breaker was connected to be energized either by closure of an automatic protection switch or by closure of the trip contact of a three-position neutral return switch of the manually operated type. Closure of the automatic protection switch energized a lock-out relay for the duration of the fault to prevent premature energization of the close coil of the latching circuit breaker by manual closure of the close contact of said three-position switch. With that arrangement it was usually considered necessary to employ one or more indicator lights for providing a visual indication of the condition of the latching circuit breaker. In certain airplane installations having as many as nine or more latching circuit breakers a correspondingly large number of indicator lights was necessary, creating confusion and consuming considerable space on an indicator panel.

A general object of this invention is to provide an improved control circuit arrangement for a latching circuit breaker which avoids the need for separate indicators such as lights to represent the condition of the latching circuit breaker. More specifically, it is an object to provide such a control circuit performing all the functions of the previous circuits, but wherein a two-position switch is employed in lieu of the former three-position switch and which is so arranged that its setting may be observed visually and represents the existing condition of the latching circuit breaker.

With these and other objects in view, the invention resides in the novel control circuit arrangement including the two-position switch means and related components connected thereto as will be described hereinafter in connection with the accompanying drawing constituting a simplified schematic diagram of the control circuit.

Referring to the drawing, the latching circuit breaker 10 incorporates power contacts 10a interposed in the power conductor 12 interconnecting the load and the power source terminal 14. A power contactor 10b in the latching circuit breaker closes the power contacts 10a when the close coil 10c is energized. Opening of said power contacts is effected by energization of the trip coil 10d. Control contacts 10e are connected in series with the energizing circuit for close coil 10c and similar contacts 10f are connected in series with the energizing circuit for the trip coil 10d. A contactor 10g is adapted to engage the two sets of control contacts 10e and 10f

alternately. Actuation of contactor 10g is effected by a delayed sequence mechanism in response to movement of the main power contactor 10b between its open and closed positions. This delayed sequence mechanism, common in such latching circuit breakers, is arranged to move the control contactor 10g abruptly from engagement with contacts 10f into engagement with contacts 10e after the power contactor 10b reaches open position, and alternatively, to move the control contactor 10g abruptly from engagement with contacts 10e into engagement with contacts 10f after the power contactor 10b reaches closed position. Thus the control contactor is actuated in a manner preventing continued energization of either the close coil or the trip coil, and these coils may be designed for a relatively lower power dissipation rating. The contactors 10b and 10g hold either of their two given positions.

Latching circuit breakers generally of the type just described and with which the invention applies are used extensively in power systems and are provided for the purpose of interrupting and restoring power circuit connections from points outside the circuit breakers themselves. Most commonly such circuit breakers are controlled by one or more automatic protection devices and one or more manually operated switches. In the present illustration the latching circuit breaker 10 is subject to control by a single protection device shown in the form of an automatic overload protection device 16. However, it will be understood that the circuit breaker may be controlled by more than one automatic protection device and that the nature of these devices and the load or fault conditions to which they respond may vary. Likewise the illustrated arrangement includes but one manually operated control switch 18, and it will be understood that the circuit may be adapted to include more than one such switch.

The illustrated protection device 16 includes an overload sensing coil 16a which energizes the automatic protection switch actuator 16b to close the protection switch 16c automatically in response to, but only during, the existence of an overload condition in load circuit conductor 12. The normally open contacts of switch 16c are interposed in conductor 20 which extends from a D.C. voltage terminal 22 through a rectifier 24 to a conductor 26 connected to the trip coil 10d. A conductor 28 connects the grounded coil 30a of lock-out relay 30 to conductor 20. Trip coil 10d and lock-out relay coil 30a are therefore energized whenever protection switch 16c is closed.

Manually operated two-position switch 18 has its common terminal 18a connected to the D.C. voltage terminal 22. This switch has a trip contact 18b and an alternatively engageable close contact 18c. The trip contact is connected to conductor 26 hence to trip coil 10d, so that positioning of switch 18 to close its trip contact trips out the latching circuit breaker 10. The close contact 18c is connected to the common terminal 30b of the lock-out relay. This relay has a normally closed contact 30c connected to the close coil through conductor 32. Thus positioning of switch 18 to engage its close contact 18c causes energization of the close coil 10c if, and only if, the lock-out relay 30 is not then energized. Relay 30 also has a contact 30d which is connected to conductor 30 and which is closed by and during energization of relay coil 30a.

If, with manual switch 18 in the close position, the automatic protection switch 16c closes, the lock-out relay 30 transfers control of the latching circuit breaker from the manual switch 18 to the trip circuit including switch 16c, rectifier 24, trip coil 10d, contacts 10f and the D.C. voltage terminals. This circuit is held indefinite-

ly because contact 30d of relay 30 forms a holding circuit for the coil 30a of this relay when such coil is energized with switch 18 in its close position. If, after the emergency condition has expired, the operator wishes to reclose the latching circuit breaker power contacts 10a, he simply moves the switch 18 momentarily to its trip position, which interrupts the holding circuit for the lock-out relay, and then back to its close position, whereupon the close coil 10c becomes energized through contact 18c of switch 18 and contact 30c of switch 30. Rectifier 24, being unidirectionally conductive, prevents flow of energizing current to coil 30a when switch 18 is moved into its trip position momentarily in the reclose procedure.

It will therefore be evident that if the manually operated switch 18 is observed to be in the trip position the operator knows that the latching circuit breaker is tripped. Moreover, except in the event of an emergency, when the manually operated switch 18 is observed to be in its close position the operator knows that the latching circuit breaker is closed. If an emergency occurs to cause closure of protection switch 16c with the switch 18 in its close position, the operator will be apprised of the condition through observance of non-functioning of electrical loads and may resolve all ambiguity by a quick flip of switch 18 into and from its trip position to clear lock-out relay 30. The lock-out relay functions to prevent the operator from energizing the close coil 10c during persistence of an emergency condition which maintains protection switch 16c closed.

Thus it will be observed that the novel circuit arrangement accomplishes the foregoing and related objectives while performing all the control and protective functions of prior circuits, and that it accomplishes these results by the substitution of one type of switch for another and by the addition of one rectifier which may be a small silicon or other rectifier since it is required to carry current only for the brief interval required to trip the latching circuit breaker whereupon the contacts 10f become disengaged by contactor 10g. By this simple substitution and addition not only is indicator panel space saved, but an indicator light and its control relay are eliminated, as previously described.

I claim as my invention:

1. In combination with a latching circuit breaker having main power contacts, a close coil energizable to close said main power contacts, a trip coil energizable to open said main power contacts, control contact means operable with opening of said main power contacts to form an energizing connection for said close coil and further operable with closing of said main power contacts to form an energizing connection for said trip coil; a direct voltage source, automatic protection means including a normally open protection switch connected in series with said source and said trip coil, a unidirectionally conductive device interposed in the connections between said protection switch and said trip coil to permit energization of said coil from said source by closure of said protection switch, a manually operated two-position switch having a common connection to the direct voltage source and having alternatively engageable trip and close contacts, a lock-out relay having a control coil connected to the interconnection between

5 the protection switch and said unidirectionally conductive device to be energized by closure of said protection switch, said lock-out relay having normally closed contacts opened by energization of said relay coil and connected between said close coil and the close contact of said two-position switch, said relay further having normally open holding contacts closed by energization of said relay coil and connected between said relay coil and the close contact of said two-position switch to form a holding circuit for said relay upon energization of said relay coil with said manually operated switch in the position to engage its close contact, and means connecting the trip contact of said two-position switch to said trip coil to form an energizing circuit for said trip coil through said energizing connection therefor by closure of said trip contact of said two-position switch, positioning of said two-position switch to engage its close contact with said relay coil deenergized forming an energizing circuit for said close coil through the energizing connection therefor, whereby the position of said two-position switch normally indicates the condition of said latching circuit breaker.

2. In combination with a latching circuit breaker having main power contacts, a close coil energizable to close said main power contacts, a trip coil energizable to open said main power contacts, control contact means operable with opening of said main power contacts to form an energizing connection for said close coil and further operable with closing of said main power contacts to form an energizing connection for said trip coil; a direct voltage source, two-position switch means connected for applying source voltage to said trip coil in one position of said two-position switch means and for applying source voltage to said close coil in the other position of said two-position switch means, a rectifier, and a protection switch connected between said trip coil and said direct voltage source, said rectifier being connected between said trip coil and said protection switch, with the latter arranged to be actuated for applying source voltage to said trip coil, through said rectifier, and relay means connected to the interconnection between said rectifier and said protection switch for energization by actuation of said protection switch, said relay means having a normally closed contact opened by energization of such relay means and connected, when opened, to interrupt the application of source voltage by said two-position switch means to said close coil, said relay means also having a normally open contact closed by energization of such relay means and connected, when closed, to apply source voltage to said relay means through the two-position switch means in said other position thereof.
